Inventor:
Earle G. Winston,

by Albert G. Davis
His Attorney.

UNITED STATES PATENT OFFICE.

EARLE G. WINSTON, OF PITTSFIELD, MASSACHUSETTS, ASSIGNOR TO GENERAL ELECTRIC COMPANY, A CORPORATION OF NEW YORK.

WINDINGS FOR ELECTRICAL APPARATUS.

1,386,828.

Specification of Letters Patent.

Patented Aug. 9, 1921.

Application filed September 18, 1920. Serial No. 410,735.

To all whom it may concern:

Be it known that I, EARLE G. WINSTON, a citizen of the United States, residing at Pittsfield, in the county of Berkshire, State 5 of Massachusetts, have invented certain new and useful Improvements in Windings for Electrical Apparatus, of which the following is a specification.

My invention relates to windings for electrical apparatus and has for its object an improved arrangement of parts which is both economical and readily manufactured.

More specifically, my invention relates to an arrangement of windings having portions connected in multiple for poly-phase transformers and the like whereby the interlacing of the conductors leading to the windings may be readily accomplished in an economical manner.

20 In low voltage and particularly in electric furnace practice, where alternating currents of high values are employed, great difficulty is experienced in economically transmitting the current from the transformer which is generally employed to supply the current to the electrodes of the furnace or other apparatus served. In order to accomplish economical transmission, special consideration must be paid to both the shape 25 and relative position of the conductors employed.

Due consideration for the so-called "skin-effect" or tendency of the alternating current transmitted to seek the section of the 30 conductor nearest the surface has led to the use of conductors of a relatively thin and flat shape, such as are often designated "copper strap."

The other main consideration which 35 determines the position of the conductors involves the problem of reducing the self-induction of these transmitting conductors. The solution of this problem is found in the practice of interlacing; that is, the conductors and their leads to the transformer coils are arranged consecutively to have alternate polarities. Hence for any instant 40 when the current in the first conductor of a bank leading from a furnace or like transformer makes the conductor's polarity plus, the next should be minus, the next plus, etc.

When the windings of the supplying transformer are all on one or two legs, the desired sequence in polarities is had by bringing the leads from the coils all out in one

group and bending them up in consecutive order. When, however, the windings are on three or more legs, the conditions of clearance between the winding stacks on the different legs do not as a rule permit 50 the grouping together of all the leads from two adjacent coil stacks. Consequently voluminous and bulky cross-over structures have been heretofore employed, bringing the lead from the side where it necessarily 55 emerges to the position of its desired sequence. This practice of employing cross-overs was expensive both to construct and in the necessary size of the tank or casing employed to house the transformer.

In the practice of my invention the use of any cross-over construction is rendered unnecessary in polyphase transformers having windings on three or more legs, because I make use of an improved arrangement of 70 windings which permits bringing the leads from the coils out on either side of the winding stack in any desired order. This I accomplish by making use of a certain number of reversely wound coils for changing 75 the original sequence and hence achieving the desired sequence of polarities when the leads are brought out and conveniently grouped between adjacent coil stacks.

For a more complete understanding of the 80 nature and objects of my invention, reference should be had to the following detailed description when taken in conjunction with the accompanying drawing in which:

Figure 1 is a diagrammatic representation of a three-phase transformer embodying my invention, while Fig. 2 is a perspective view of a three-phase transformer as 85 actually constructed removed from its casing which embodies my invention.

Referring now to the drawings, 10 denotes a core having a plurality of legs 11, 12 and 13, which support windings 14, 15 and 16, respectively.

The windings 14, 15 and 16 are of the 100 interleaved disk coil type, in which the coils P denote high voltage coils and those designated by S the low voltage. Since the low voltage coils S are to supply currents of high values, it is with the interlacing of 105 the leads to these coils that my invention principally relates.

In order to approximate conditions where my invention applies, it will be assumed that for reasons of clearance that it is per-

95

110

115

missible to group all the leads of winding 15 neither on the left hand side, nor all on the right hand side, so that some must be grouped with the lead brought out from 5 each of windings 14 and 16.

Consider now winding 14. Suppose that the coil designated S-20 is wound as a right hand wound helical spiral (diagrammatically indicated by the backwardly pointing 10 arrow) which starts from the top lead denoted 31, it will then finish with the bottom lead 32.

If at the instant of reckoning, the polarity of lead 31 is plus, then the polarity of lead 15 32 is minus as designated in the drawing. The sequence of alternate polarities is then had by bringing the lead 32 up on the right of lead 31. Similarly, to continue the sequence the coil denoted S-21 must be like 20 coil S-20, that is, it must be a right hand wound helical spiral (denoted by the backwardly pointing arrow) so that its top lead 33 which would have plus polarity at the instant of reckoning is again led up to the 25 right beside lead 32 and thus alternates with its polarity. Bottom lead 34, which has a negative polarity at the instant of reckoning, is then led up beside lead 33 on its right.

30 It thus appears that the desired sequence in polarities is had for the parallel connected low voltage coils of winding 14 by bringing the leads thereof out on one side in regular order.

35 Consider now the winding 15: We will suppose that the before-mentioned considerations of clearance permit that the leads of only one coil, for instance that designated S-22, be brought out and grouped with leads 40 31, 32, 33 and 34. To avoid a cross-over construction the bottom lead indicated at 35 must be led back and brought up to the right of lead 34 and the top lead 36 led up to the 45 right of lead 35. The desired sequence of polarities require that lead 35 shall be plus at the instant of reckoning and that lead 36 shall be minus, which requires that coil S-22 should also be a left hand wound helical spiral (denoted by the forwardly pointing 50 arrow).

Coil S-23, according to the conditions of clearance assumed, will have its leads 37 and 38 brought up at the right side of winding 15.

55 In order however, to get the desired sequence in polarity in the leads, and in order also to avoid a cross-over construction, where my invention is practiced, the coil whose leads are differently grouped from another 60 on the same winding axis must be oppositely wound. The coil S-23 is therefore again a right hand wound helical spiral (denoted by the backwardly pointing arrow). The top lead 37 thus has plus polarity at the instant of reckoning while lead 38 is minus.

In the winding 16, the coils S-24 and S-25 have their leads associated with leads 37 and 38. Since the leads from these coils, the same being denoted 26, 27, 28 and 29, are all in the same group, the coils are both wound 70 in the same direction. The proper sequence, as will be seen, is had by bringing lead 26 from the bottom turn of coil S-25, etc.; the two coils being wound as left hand wound helical spirals (signified by the forwardly 75 pointing arrows) to give this sequence.

To further exemplify the practice of my invention I now describe the embodiment shown in Fig. 2 which illustrates a three phase transformer particularly adapted to 80 supply an electric furnace.

The core has three legs 41, 42 and 43 while the yokes are inclosed in upper and lower core clamps 44 and 45 respectively which also serve as supports for the three stacks of 85 windings 46, 47 and 48 which respectively surround the three legs.

The leads 51 to 56 from the low voltage coils or portions of winding 46 are brought out all on the right side and led up in order 90 and secured in the terminal board 70, which is secured on the top of core clamps 44. The three low voltage portions on this leg as a consequence are all wound in the same direction, that is, they may all be taken as right 95 hand wound helical spirals.

In like manner the low voltage portions in the winding 48 have all their leads 63 to 68 brought out in order on the left side thereof instead of the right, so that these 100 portions also are all wound in the same direction. Since, however, the magnetic flux of leg 43 is of the same direction, except for phase difference, as that of leg 41, these portions must be wound oppositely to those on 105 leg 41, that is, they may be taken as left hand wound helical spirals.

Winding 47 has the leads 57 to 62 of its low voltage portions brought out partly on one side to be grouped with leads 51 to 56 110 and partly on the other to be grouped with leads 63 to 68. The desired sequence of polarities is obtained and a cross-over construction avoided by taking the portion supplying current to leads 57 to 58 as a left 115 hand wound helical spiral, while the portions supplying leads 59 to 62 with current are taken as right hand helical spirals.

By this construction, it is seen that a casting on which the cover 71 (mounted on the 120 superstructure of the transformer) will fit, need have only sufficient clearance to clear the superstructure of the transformer without giving special consideration to the electrical factors involved.

Having now described an embodiment of my invention which is at present the best means known to me for carrying the same into effect, I would have it understood that this is merely illustrative and that I do not mean 130

to be limited thereby to the precise details shown, nor restricted in the choice of recognized equivalents except as defined in my claims hereunto annexed.

- 5 What I claim as new and desire to secure by Letters Patent of the United States, is:—
1. An electrical apparatus comprising in combination, a core provided with a plurality of legs, and windings on each of said legs having portions provided with leads adapted for interlaced connection, a portion on one leg being wound in a direction opposite that of another portion thereon, the leads of said portions being arranged in 10 different groups whereby a sequence of alternate polarities among the leads is accomplished without cross-over connections.
  2. A polyphase electrical apparatus comprising in combination, a core provided with 15 a plurality of legs, and windings on each of said legs having portions adapted to be connected in multiple with their leads arranged to have alternate polarities, a portion of the winding on one leg being wound 20 in a direction opposite to that of another portion thereon, said portions having their leads arranged respectively in different groups whereby the desired sequence of polarities is had without crossover connections.
  3. A polyphase electrical apparatus comprising in combination, a core provided 25 with a plurality of legs, and windings on 30

each of said legs having portions adapted to be connected in multiple with their leads arranged to have alternate polarities, a predetermined portion of the winding on an intermediate leg being wound in a direction opposite that of the remaining portion thereon, the leads from the first named portion being brought out on one side of the 40 winding and associated in a group, the leads from the remaining portion being brought out on the other side and associated in another group whereby the sequence of alternating polarities is had without the use of 45 cross-over connections.

4. A three-phase transformer comprising in combination, a core having three legs, and windings on each leg, said windings having coils provided with leads adapted 50 for connecting them in multiple and arranged to have alternate polarities, a predetermined number of coils on the central leg being wound in a direction opposite that of the remaining coils, the leads of the first- 55 mentioned coils being brought out on one side and associated in one group and those of the remaining coils being brought out on the other side and associated in a second group.

In witness whereof, I have hereunto set my hand this thirteenth day of September, 1920.

EARLE G. WINSTON.
